UNITED STATES PATENT OFFICE.

HERMAN SCHLAICH, OF LONG ISLAND CITY, NEW YORK.

DESIGN FOR A COMBINED CASING AND DIAL.

Application filed May 12, 1921. Serial No. 469,058. Term of patent 14 years.

To all whom it may concern:

Be it known that I, HERMAN SCHLAICH, a citizen of the United States, residing in Long Island City, county of Queens, and State of New York, have invented a new, original, and ornamental Design for a Combined Casing and Dial, of which the following is a specification, reference being had to the accompanying drawing, forming a part thereof.

Figure 1 is a plan view of the combined casing and dial.

Figure 2 is a side view thereof.

What I claim is—

The ornamental design for a combined casing and dial, as shown.

HERMAN SCHLAICH.
